UNITED STATES PATENT OFFICE

HAROLD D. PAGE, OF DEPEW, NEW YORK, ASSIGNOR TO WAUGH EQUIPMENT COMPANY, OF CHICAGO, ILLINOIS, A CORPORATION OF MAINE

CUSHIONING MEANS FOR DRAFT GEARS

Application filed June 29, 1929. Serial No. 374,826.

This invention relates to cushioning means for draft gears for absorbing ultimate blows and preventing metal to metal contact of parts which usually proves so disastrous to the gears.

The invention comprises the novel structure and combinations of parts hereinafter described and more particularly pointed out and defined in the appended claim.

10 In the accompanying drawings which illustrate a preferred form of this invention and in which similar reference numerals refer to similar features in the different views:

On the drawings:

15 Figure 1 is a sectional view thru a draft gear housing showing the draft gear in elevation with parts broken away to illustrate this invention.

Figure 2 is a plan view of a buffing unit used in connection with this invention.

Figure 3 is a fragmentary sectional view thru the draft gear casing illustrating the buffing unit in its normal position.

20 Figure 4 is a view similar to Figure 3, illustrating the buffing unit in its compressed and expanded position.

As shown on the drawings:

In connection with this invention, there is shown a draft gear housing 1, having two 25 pairs of interior spaced abutments 2 between which the draft gear casing 3 is mounted. The casing 1 contains the usual friction elements which are actuated by a projecting wedge member 4. The particular structure 30 of the friction elements and their cooperating parts is not illustrated as they form no part of this invention. Any friction elements within the casing will answer in accordance with this invention which concerns 35 itself more directly with means for cushioning the draft gear as a whole irrespective of its particular structure.

According to the invention, suitable cushioning or buffing elements are interposed between one end of the draft gear casing 3 and the follower block 5 which is engaged by the yoke 6 of the coupler 7. While these buffing elements may assume various forms and may be interposed in different ways, as 40 a matter of illustration, they are shown as

consisting of spaced concentric oblong strips 8, 9 and 10 of rubber or the like embedded or confined in suitable grooves in the rear end of the draft gear casing 3. The spaces between the strips are such as to allow for proper compression or expansion. 55

When any thrust is applied to the draft gear by the yoke of the coupler, these rubber cushioning or buffing elements will be more or less compressed, and if the blow or shock is sufficient, they will be compressed and expanded as shown in Figure 4, but under all conditions, they will produce a yield or cushioning effect and eliminate any metal to metal contact, thereby preventing destruction or injury to parts that might arise under excessive or ultimate blows. 60 65

I am aware that many changes may be made, and numerous details of construction may be varied through a wide range without departing from the principles of this invention, and I therefore do not purpose limiting the patent granted hereon, otherwise than necessitated by the prior art. 70

I claim as my invention:

Draft gear including a casing enclosing stress absorbing elements and having a series of annular grooves on its rear face, a yoke embracing the casing, a follower block between the yoke and casing, and rubber rings mounted in and projecting from said 80 grooves and engaging said follower block.

In testimony whereof I have hereunto subscribed my name at Depew, New York, Erie County. 85
